UNITED STATES PATENT OFFICE.

WILLIAM M. SHUTT, OF NORTH WASHINGTON, PENNSYLVANIA.

CHECKING DEVICE.

SPECIFICATION forming part of Letters Patent No. 608,920, dated August 9, 1898.

Application filed August 14, 1897. Serial No. 648,269. (No model.)

To all whom it may concern:

Be it known that I, WILLIAM M. SHUTT, a citizen of the United States, residing at North Washington, in the county of Westmoreland 5 and State of Pennsylvania, have invented certain new and useful Improvements in Check-rein Attachments; and I do hereby declare the following to be a full, clear, and exact description of the invention, such as will enable others skilled in the art to which it appertains to make and use the same.

This invention relates to a checkrein attachment for harness, the object being to provide means whereby the checkrein may be checked up or loosened to the desired extent without necessitating the dismounting of the driver.

To the accomplishment of this object the invention consists in providing a saddle-hook 20 over which the checkrein may be checked in the usual manner, provided with slots through which a supplemental checkrein may be passed when it is desired to employ a hook in connection with my invention, and, further, 25 in providing a supplemental-checkrein hook of peculiar construction located upon the back-strap immediately forward of the crupper and designed to adjustably retain the supplemental checkrein, which may be adjusted by a person within the vehicle.

Referring to the drawings, Figure 1 is a general view showing the application of my device. Fig. 2 is a detail perspective view of my improved saddle-hook. Fig. 3 is a similar view of the check-hook.

Referring to the numerals on the drawings, 1 indicates the saddle, and 2 the back-strap, of an ordinary harness, upon the former of which is located my improved saddle-hook 3, 40 and upon the latter of which is secured at a point in front of the crupper my improved check-hook 4. The saddle-hook 3 is preferably composed of a base-plate 5, provided with suitable apertures for the reception of 45 rivets, bolts, or the like, by means of which the plate is secured to the saddle, and at its forward end with an upwardly-projecting slotted plate 6, from which extends upwardly and rearwardly a saddle-hook 7, beyond the 50 rear extremity of which is located a slotted guard 8, projected upwardly from the base-

plate at a slight distance from its rear extremity.

When the device is designed for use in an ordinary connection, the checkrein 9 is looped 55 over the hook in the ordinary manner, but where it is desired to employ the saddle-hook in connection with the other elements of my invention a supplemental checkrein 10 is passed through the slots in the end plate and 60 guard and is connected at its forward extremity, as by a snap-hook 11, with the checkrein. The supplemental rein is then extended rearwardly to the vehicle and is provided with a series of apertures 12, which are de- 65 signed to engage a check-hook 13, projecting from the base-plate 14, provided in front of said hook with a strap-loop 15, designed to receive the supplemental checkrein and to insure the engagement thereof with the check- 70 hook.

17 indicates a ring or other means located at the rear end of the supplemental rein, by means of which it may be secured to a hook 18 or the like screwed upon the dashboard of 75 the vehicle. It will be observed that the driver by reaching forward can disengage the supplemental checkrein from the check-hook and can then draw the rein tighter or loosen it and thereafter cause its engagement with 80 the check-hook to retain the horse's head at the desired elevation, and it will be obvious that by employing this simple device the horse can be uncheckered—as, for instance, where it is desired to water the animal—with 85 out the necessity for the driver leaving the vehicle and that the horse can be checked to the desired extent with equal facility.

While the present embodiment of my invention appears at this time to be preferable, 90 I do not desire to limit myself to the details of construction herein shown and described, but reserve the right to change, modify, or vary the same at will within the scope of my invention.

Having thus described the invention, what I claim as new, and desire to secure by Letters Patent, is—

In a device of the character described, the combination with a base-plate, an upwardly-extending rigid terminal plate slotted and provided above the slot with an upwardly and

rearwardly extending fixed hook and a slotted guide adjacent to the opposite end of the base-plate located behind the extremity of the hook and extending parallel to the terminal plate, 5 of a checkrein, a supplemental checkrein secured at one end to the checkrein, passing through the slot in the terminal plate and located below the hook and provided with a series of apertures and a check-hook located in 10 the rear of said saddle-hook comprising a base-plate, a strap-loop at its front end, and an upwardly and rearwardly extending hook

rigidly secured to the base-plate behind the strap-loop, and designed to engage the apertures in the supplemental checkrein, substantially as specified. 15

In testimony whereof I have signed this specification in the presence of two subscribing witnesses.

WILLIAM M. SHUTT.
